UNITED STATES PATENT OFFICE.

PETER KRUSE, OF BROOKLYN, NEW YORK, ASSIGNOR TO E. W. BLISS COMPANY, OF BROOKLYN, NEW YORK, A CORPORATION OF WEST VIRGINIA.

FLANGING MACHINE FOR CAN BODIES.

1,403,120.

Specification of Letters Patent. Patented Jan. 10, 1922.

Application filed October 21, 1920. Serial No. 418,435.

To all whom it may concern:

Be it known that I, PETER KRUSE, a citizen of the United States, residing in the borough of Brooklyn, county of Kings, city and State of New York, have invented certain new and useful Improvements in Flanging Machines for Can Bodies, of which the following is a specification.

This invention relates to can machinery or devices, and aims to provide improvements therein.

In the practical art of can making, considerable difficulty has been encountered in developing a machine or device capable of satisfactorily flanging can bodies which are polygonal in shape, especially at a speed for quantity production.

The present invention provides a machine capable of producing satisfactory flanges, upon can bodies of polygonal shape, and capable of performing the flanging operation at a rapid rate. The invention furthermore provides a machine or device in which the construction is simple, efficient and durable.

An embodiment of the invention is illustrated in the accompanying drawings, wherein Fig. 1 is a longitudinal, sectional view of the middle and one end or side of said embodiment.

Fig. 2 is a view similar to Fig. 1, showing the parts in a different operative position.

Fig. 3 is a sectional view, at right angles to the section in Figs. 1 and 2.

Fig. 4 is a detail view of the slide 20, and associated parts.

Referring to said drawing, X indicates a can body.

The numeral 10 designates the means for turning over the edge or edges of a can body, for the purpose of forming a flange, such as indicated by the letter x, Fig. 2.

Suitable means 11 are provided for confining the can body, preferably both exteriorly and interiorly, during the flange forming operation.

These means preferably comprise the outer or female form 12, comprising the separable bodies 13 and 14, and the male form 15.

The part 14 of the form conveniently forms a part of a spider or drum 16, upon an axial support 117. The part 13 of the form is conveniently mounted on an arm 17, pivoted, as indicated at 18, upon a slide 20

having movement toward and from the open end of the can body. A spring 22, serves to press the arm 17, carrying the part 13, away from its closed position, and a cam 24, adapted to contact with a roller 25, on the arm 17, serves for moving the part 14 to its closed position.

The form 15 is conveniently connected to and carried by the slide 20, and, hence, moves with the slide into and out of the can body X. Bolts 21 serve to connect the form 15 to the slide 20.

The edge-turning or flange-forming means 10, are also conveniently carried by the slide 20. The flange-turning means 10 preferably comprises a plurality of segments 30, preferably having a movement along radial lines, and adapted to move across the planes of the edges of the can body, for the purpose of turning said edges to form a flange. 70 Where an out-turned flange is to be formed, the segments 30, in their collapsed position, are adapted to enter the open end of the can body, and, when these segments are expanded or spread, they move outward across 80 the planes of the sides of the can bodies, turning such edges over and forming thereon a flange x. The hollow or female form 12 is formed with a corner 32, against or around which the edge of the can body is turned to 85 form the flange, and there is a space 33, beyond the corner 32, which allows the edge portion of the can body to turn. Moreover, the segments 30, preferably engage the edge of the can body closely adjacent to the corners 32, and preferably wipe or slide past the turned edges, and further preferably press or flatten them against a portion or face of the form.

Means are provided for limiting or determining the amount of projection of the edge portion of the body X over or beyond the shoulder or corner 32, on the form 12, thereby determining the width of the flange x, and also bringing about a uniformity in 100 the width of said flanges x. These means are conveniently in the form of a shoulder or "step" 34 on the segments 30. When the segments are collapsed, the shoulder 34 projects beyond the edges of the can body, and, 105 when the slide or slides 20 move the group or groups of segments toward the can bodies in the forms 12, the segments enter the can body until the shoulder 34 strikes the edge of the can body, and, if this contact is made 110

prior to the time the slide 20 completes its movement, the can body will thereafter move with the slide and segments 30 thereon, thus being centered or located by the 5 action of said slide, segments, and shoulder 34 thereon.

Means, such as springs 37, may be provided for normally collapsing the segments 30, and means, such as a wedge-block 39, is 10 conveniently provided for spreading or expanding the segments. Slots 41 in the segments 30, admit of movement of the said segments on the bolts 21.

The wedge-block 39 is preferably carried 15 upon a rod 47, slidably mounted in the slide 20. A spring 50 serves for normally retracting the rod 47, and a cam 52, acting upon a roller 53 on the said rod 47, serves to press said rod to cause the wedge-block 39 20 to spread the segments 30.

The movements of the slide 20 are preferably controlled by a cam 55 engaging a roller 56 on the said slide 20.

A plurality of confining means 11, and 25 flange-forming means 10, constituting a unit, are provided, and these units are preferably arranged symmetrically around a shaft or axial support 117, as shown in Fig. 3. The cam 55 is arranged co-axially, or upon the 30 shaft 117. The cam 24 is also preferably arranged co-axially with the shaft or support 117.

The cams 24, 52, and 55, on the one hand, and the confining means, or edge-turning, 35 or flange-forming means, on the other hand, are made relatively movable, whereby a continuously working machine may be provided. To this end, the unit or units of confining and edge-turning means are preferably made rotatable, such rotation being conveniently effected through the shaft 117. Rods 60, passing through the side frame of the machine, and fastened to the cam 55, prevent said cam from turning. The cam 24 40 is conveniently connected to tie-rods 62, connecting the side frames of the machine.

Where two ends of a can body are to be flanged, as is usually the case, the flanging construction is duplicated on opposite sides 50 of the machine.

Operation: Can bodies from a chute 70, preferably drop into the portions 14 of the form 12, during the rotation of the forms past said chute. During this part of the 55 movement, the springs 22 act upon the arms 17 to separate or spread the part 13 of the form from the part 14, and the cam 55 acts on the slide 20, in such manner as to draw the part 13 of the form, and the male form 60 15, out of the path of the can body as it drops into the part 14 of the form 12. Thereupon, the cam 55 acts to push the slide 20 toward the can body, and the form 15 enters the can body, and, thereupon, or simultaneously, the roller 25 comes in contact 65

with the cam 24, and pushes the arm 17, carrying the part 13 of the form 12, toward the part 14, to close the form.

When the slide 20 moves toward the can body, the group of segments 30 are collapsed, and partially enter the can body. The shoulder 34 thereof, if the cans are not properly "centered" or located in the form, comes in contact with the edge of the can body and pushes it to one side, to a "centered" or 75 properly located position.

When the part 13 is closed upon the part 14, so as to confine the can body, cam 52 acts upon roller 53 of the rod 47, carrying the wedge-block 39, and causes said wedge-block to spread or expand the segments 30 of the die or edge-turning means 10. The extent to which the segments 30 project into the can body being limited by the shoulder 34, the width of the flange formed in the can body by the expansion of the segments is constant. The movement of these segments against the projecting edges of the can body causes these projecting edges to be turned around the corners 32 of the form, thereby 85 forming the flange α . Preferably, the segments act to slide against the sides of the turned over edge, and presses and flattens the said edges or flanges against the form.

Thereupon, the roller 25 passes off of the cam 24, allowing the spring 22 to push away the arm 17, thereby moving away the part 13 of the form, and opening the form. The cam 55 then acts upon the slide 20, through the roller 56, to withdraw the form 15. At 100 this instant, the can body may be discharged. The discharge is conveniently effected by arranging the machine so that the form opens, after the flanging operation, at the under side of the machine, so that the can body falls out, by gravity, onto a chute or discharge plate 80.

The inventive ideas herein set forth may receive other embodiments than those herein specifically illustrated and described.

What is claimed is:

1. A flanging machine for can bodies, or the like, comprising means for confining said can-body with the edge which is to be turned to constitute the flange, free to be turned, and a device adapted to move across the planes of the edges, and thereby adapted to turn said edges to form the flange, said edge-turning device comprising a die having segments and means for operating said segments, said segments being movable radially and said operating means operating to simultaneously move said segments against and across the edges of said can body.

2. A flanging machine for can-bodies, or the like, comprising means for confining said can-body with the edge which is to be turned to constitute the flange, free to be turned, and a device adapted to move across the planes of the edges, and thereby adapted to 125 130

- turn said edges to form the flange, said edge-turning device comprising a die having segments and a wedge-block for moving said segments, said segments being movable radially, and said wedge block operating to simultaneously move said segments against and across the edges of said can body.
3. A flanging machine for can-bodies, or the like, comprising means for confining 10 said can-body with the edge which is to be turned to constitute the flange, free to be turned, a device adapted to move across the planes of the edges, and thereby adapted to turn said edges to form the flange, and a 15 slide movable axially toward and from the open end of the can-body, said edge-turning device being mounted on said slide.
4. A flanging machine for can-bodies, or the like, comprising means for confining 20 said can-body with the edge which is to be turned to constitute the flange, free to be turned, a device adapted to move across the planes of the edges, and thereby adapted to turn said edges to form the flange, and a 25 slide movable axially toward and from the open end of the can-body, said edge-turning device being mounted on said slide, and means for determining the extent to which the flange-turning device laps the edge of 30 the can-body, whereby the width of the flange is determined.
5. A flanging machine for can-bodies, or the like, comprising means for confining 35 said can-body with the edge which is to be turned to constitute the flange, free to be turned, a device adapted to move across the planes of the edges, and thereby adapted to turn said edges to form the flange, and a 40 slide movable axially toward and from the open end of the can-body, said edge-turning device being mounted on said slide, and means for moving said slide toward and from said can-body.
6. A flanging machine for can-bodies, or the like, comprising means for confining 45 said can-body with the edge which is to be turned to constitute the flange, free to be turned, a device adapted to move across the planes of the edges, and thereby adapted to 50 turn said edges to form the flange, and a slide movable axially toward and from the open end of the can-body, said edge-turning device being mounted on said slide, said slide also having thereon a form comprising 55 a part of said confining means.
7. A flanging machine for can-bodies, or the like, comprising means for confining 60 said can-body with the edge which is to be turned to constitute the flange, free to be turned, a device adapted to move across the planes of the edges, and thereby adapted to
- turn said edges to form the flange, and a slide moving axially toward and from the open end of the can-body, said edge-turning device being mounted on said slide, said edge-turning device comprising a die having radially movable segments, and means for moving said segments, said means comprising a rod movable upon said slide.
8. A flanging machine for can-bodies, or the like, comprising means for confining 70 said can-body with the edge which is to be turned to constitute the flange, free to be turned, a device adapted to move across the planes of the edges, and thereby adapted to 75 turn said edges to form the flange, and a slide movable axially toward and from the open end of the can-body, said edge-turning device being mounted on said slide, said edge-turning device comprising a die having 80 radially movable segments, and means for moving said segments, said means comprising a rod movable upon said slide, means for moving said slide toward and from said can-body, and means for moving said segment operating rod to actuate said segments.
9. A flanging machine for can-bodies, or the like, comprising means for confining 85 said can-body with the edge which is to be turned to constitute the flange, free to be turned, a device adapted to move across the planes of the edges, and thereby adapted to 90 turn said edges to form the flange, said confining means and edge-turning means being plural and rotatable as units around an axis, and a cam for operating said edge-turning means.
10. A flanging machine for can-bodies, or the like, comprising means for confining 95 said can-body with the edge which is to be turned to constitute the flange, free to be turned, and a device adapted to move across the planes of the edges, and thereby adapted to 100 turn said edges to form the flange, a slide movable axially toward and from the open end of the can-body, said edge-turning device being mounted on said slide, said edge-turning device comprising a die having 105 radially movable segments, and means for moving said segments, said means comprising a rod movable upon said slide, said confining means and edge-turning means being plural and rotatable as units around an axis, a cam for operating said slides, and a 110 cam for operating said rod.

In witness whereof, I have hereunto signed my name.

PETER KRUSE.
